UNITED STATES PATENT OFFICE

2,488,035

MIRROR-LINED CELLARETTE

William R. Pistone, Kansas City, Mo., assignor of
one-half to Albert Anch

Application May 8, 1946, Serial No. 668,215

2 Claims. (Cl. 312—172)

1

This invention relates to cabinets and more particularly to cabinets and/or cellarette structures, such as are used for containing glassware and bottled goods.

There have been various types of cellarettes and much effort has been expended in enhancing the external appearance thereof, but the interiors are usually bare wood and are unattractive, and the interiors are exposed to view at all times when the cellarettes are in use. Single mirrors have been used on cellarettes where there are back bars provided in connection therewith, and such mirrors are usually mounted in frame or by a number of fastening devices extending through the glass panel. The glassware and other equipment usually contained in cellarettes are of various and attractive designs but attractive equipment on a bare background does not show up to a good advantage.

The principal object of the present invention is to provide a cellarette and/or cabinet with a mirror lining to enhance the appearance thereof and the equipment usually contained therein, to provide novel means for mounting mirrors in the cellarette whereby relative expansion or contraction of the mirrors and cellarette walls will not exert any strain to crack and break the mirrors; to provide space between the mirrors and walls; to provide for positioning glassware holders in the cellarette in such a manner that they are reflected in the various mirrors to give the effect of increased size and quantity of equipment; to provide means for illuminating the interior of the cellarette and to provide a cellarette that is sturdy, durable, yet presenting a delicately, beautiful interior when it is opened for use, and to provide hidden storage for the bottled goods normally contained in cellarettes and to provide a cellarette with all portions thereof easily accessible and easily cleaned, yet is adaptable for any variation in external design.

In accomplishing these and other objects of the present invention, I have provided improved details of structure, the preferred forms of which are illustrated in accompanying drawings herein:

Fig. 1 is a perspective view of a cellarette embodying the features of the present invention and particularly illustrating the interior of the cellarette as when opened or in use.

Fig. 2 is a vertical transverse section through the cellarette on the line 2—2 of Fig. 1.

Fig. 3 is a horizontal sectional view through the upper compartment of a cellarette.

Fig. 4 is a detailed sectional view on the line

2

4—4 Fig. 1, particularly illustrating the mounting of the mirrors in said cellarette.

Referring more in detail to the drawings:

1 designates a cellarette consisting of rear wall 5, side walls 3 and 4 suitably connected to the rear wall adjacent the side edges 5 thereof. The cellarette is provided with a bottom 6 having its edges suitably secured to the rear and side walls in space relation to the bottom ends thereof as at 7. Co-extensive with the rear wall and secured to the top edge thereof and the top edges of the side walls is a cover member 8 of suitable width to extend substantially midway of the side wall as at 9. Suitably connected to the front edge 10 of said cover member and preferably by hidden type hinges 11 is a front cover member 12 adapted to close the remainder of the top of the cellarette not covered by the cover member 8, the hinges 11 being such that the cover member 12 will fall back over and rest on the cover member 8 when the cellarette is in use. A mirror 13, preferably mounted in a suitable frame 14, is secured to the surface 15 of the cover member 12 whereby said mirror forms a serving surface when the cover member 12 is opened and the cellarette in use. When the cover member is moved to a closing position the mirror is on the under side of said cover member and inside of the cellarette.

Preferably mounted in the cellarette substantially midway the height between the bottom 6 and the cover member 8, is a partition or shelf 16 dividing the cellarette into upper and lower compartments 17 and 18 respectively. The edges of the partition 16 are suitably secured to the rear and side walls 2, 3 and 4. The lower compartment 18 is provided with a grooved frame 19 mounted substantially midway the depth of the lower compartment, said frame being connected to the side walls 3 and 4, bottom wall 6, and partition 16. The frame 19 preferably has spaced grooves 20 and 21 adapted to receive glass panels 22 and 23 respectively, of such length that said panels overlap adjacent the center 24 whereby said panels may be moved in the grooves 20 and 21 to selectively close or open the rear portion 25 of the lower compartment 18.

The rear surface 26 of the panels 22 and 23 are silvered and provided with a suitable backing therefor, whereby when looking into the compartment 18 with the panels in closed position as shown in Fig. 1, a mirrored surface is presented. The front portion of the compartment 18 is provided with a mirror 27 resting on the bottom 6, said mirror being narrower than the distance from the front edge 28 of the bottom

and the frame 19 to provide a space 28 between the edge of the mirror and the frame 19. The side walls 3 and 4 in the compartment 18 are provided with mirrors 29 and 30, the lower edge of said mirrors resting on the bottom 6 and terminating short of the partition 16 to provide a space 31 therebetween. Mirrors 29 and 30 are of substantially the same width as the mirror 27 and arranged to provide a space 32 between the mirror 30 and the frame 19. Mirrors 29 and 30 are provided with suitable fastening devices 33 for holding frames loosely upright adjacent the side walls, there being a slight space between the mirrors and the side walls allowing air circulation therebetween. It is to be noted that there is only one fastening device for each of said mirrors. Mirror 27 terminates short of the mirrors 29 and 30 to provide suitable spacing 34 between the ends of the mirror 27 and the mirrors 29 and 30. With this arrangement there is sufficient space between the mirrors and any of the walls of adjacent surfaces permitting full expansion of said mirrors without danger of strain or cracking thereof.

In the upper compartment 17 on the inside surface of the wall 2 there is a shelf 35 having suitable apertures 36 therein for supporting glasses or other equipment in the cellarette. The shelf 35 is preferably secured to the wall 2 slightly below the center of the height of the compartment 17. Located below the shelf 35 is a mirror panel 37 resting on the partition 16 and having its upper edge terminating short of the shelf 35 and its ends spaced from the side walls 3 and 4. Said panel 37 is provided with a single fastening device 38 supporting the mirror adjacent the wall 2 and slightly spaced therefrom. Located above the shelf 35 is a panel 39 which has its lower edge resting on the shelf 35 and its upper edge terminating short of the cover member 8 as at 40. The panel 39 is also mirrored and terminates short of the side walls 3 and 4 in the same manner as the panel 37, there being a suitable fastening device for supporting said panel as illustrated in regard to the panel 37 in Fig. 4.

The side walls 3 and 4 are also provided with mirror panels 41 and 42 respectively, lower edges of which rest on the partition 16, the upper edge terminating short of the upper edge side wall as at 43. Each of the panels 41 and 42 is provided with a single fastening means 44 of the same type as shown in Fig. 4, wherein an aperture 46 is provided in the mirror panel and a screw or other suitable device 47 extends through said aperture and is threaded into the wall as at 48. The head 49 of the screw engages in a washer 50 of the larger diameter than the aperture whereby the edges of the washer engage the mirror back as at 51. It is to be noted there is spacing as at 52 between the panel and the wall whereby the panel is loosely supported adjacent the wall with clearance on two sides so the panel may expand without undue stress thereof.

Mounted on the glass panels 41 and 42 are brackets 53 and 54 preferably having openings 55 therein provided with slots 56 extending to the outer edge 57 of said brackets whereby stemware or other suitable equipment may be supported on said brackets. The brackets may be suitably supported on the panels 41 and 42; however, one form of such fastening device could be screws 58 extending through respective panels and into the brackets.

Mounted on the front edges 59 of the side walls

3 and 4 preferably by suitable hinges 60 of the hidden type are doors 61 and 62, said doors being of such size that when they are closed they close the front portion of the cellarette and cooperate with the panel at cover 12 to enclose the entire opening in the cellarette. Mounted on the inner surface of the doors are brackets 65, 66 and 67 for holding various types of glassware.

The upper surface of the partition 16 is preferably provided with a mirror panel 68 of such size that the rear inside edges terminate short of panel 37 and 41 and 42 to provide a spacing therebetween as at 69, said panel 68 being of sufficient weight that no fastening devices are required for holding the same in place. A suitable light 70 is preferably mounted on the lower side of the cover member 8 adjacent the mirror panel 39 whereby the interior of the cellarette is illuminated when desired.

In using a cellarette constructed as described, the doors 61 and 62 are opened and the cover member 12 folded back over the cover member 8 to provide access to the upper compartment 17 and the forward part of the compartment 18, thereby exposing glassware carried by the respective brackets, mounted doors, side walls and rear walls and also all equipment on the respective panels 27 and 68. The bottle goods are stored in the compartment 25 and therefore out of sight, but access can be gained thereto by moving one of the panels 22 and 23 to open said compartment 25. With this arrangement the mirrored surfaces provide an effect of increased size and depth of the cellarette and also an appearance of additional equipment therein. The mirrors may be colored if desired to further enhance the appearance of the interior of said cellarette. Each of the panels may be easily removed by the removing of one fastening device for each of them, and it is obvious that the entire interior of the cellarette may be easily cleaned and even if something is spilled therein, the appearance of walls or partition would not be affected.

It is believed obvious that I have provided a sturdy, durable cellarette providing easy access to all portions thereof and of greatly enhanced interior beauty.

What I claim and desire to secure by Letters Patent is:

50. 1. A cabinet of the character described comprising, rear and side walls, a bottom connecting the rear and side walls, a shelf connecting the rear and side walls midway the height thereof, means closing the top of the cabinet, means closing 55 the front of the cabinet, mirror panels slidably mounted between the bottom and the shelf and spaced from the rear wall to form a hidden compartment between said rear wall and the panels, mirrors on the inner surfaces of the side and rear walls and the upper surfaces of the shelf and bottom, means for loosely holding said mirrors on the surfaces, means mounted on selected mirrors for supporting glassware in the cabinet, and means in the upper portion of the cabinet for illuminating the interior thereof.

2. A cabinet of the character described comprising, rear and side walls, a bottom connecting the rear and side walls, a shelf connecting the rear and side walls midway the height thereof, a cover connecting the rear and side walls and extending substantially half the length of the side walls, a door hinged to the front edge of the cover to complete the closure of the top of said cabinet, doors hinged to the front edges of the side walls 70 for closing the front of the cabinet, mirror panels

slidably mounted between the bottom and shelf and spaced from the rear wall, said panels forming a closure for a hidden compartment between the rear wall and the panels, mirrors on the inner surfaces of the side and rear walls and the upper surfaces of the shelf and bottom, means for loosely holding said mirrors on said surfaces to allow for relative expansion, brackets mounted on selected mirrors, said brackets having recesses for receiving and supporting glassware in the cabinet whereby reflection by the mirrors provides an effect of larger cabinet size and more glassware, and means in the upper portion of the cabinet for illuminating the interior thereof.
